UNITED STATES PATENT OFFICE.

EDWIN CRAWLEY, OF NEWPORT, KENTUCKY.

HORSE-COLLAR MACHINE.

SPECIFICATION forming part of Letters Patent No. 389,690, dated September 18, 1888.

Application filed June 20, 1882. Serial No. 64,705. (No model.)

To all whom it may concern:

Be it known that I, EDWIN CRAWLEY, a citizen of the United States of America, and a resident of the city of Newport, in the county 5 of Campbell and State of Kentucky, have invented a new and useful Machine for Stuffing Horse-Collars, of which the following is a specification.

My invention, in general, enables the horse-collar to be evenly and symmetrically stuffed in an easy and expeditious manner and with economy.

The various features of my invention and their particular advantages will be obvious 15 from the following specification.

In the accompanying drawings, making part of this specification, Figure 1 represents a side elevation of a machine embodying my invention. Fig. 2, Sheet 2, is an end elevation of 20 the front end—that is to say, of that end of the machine which is at the left hand in Fig. 1, and all that portion of the machine which in Fig. 1 is at the right side of the vertical dotted line x x is omitted. The collar-holder is shown herein by dotted lines only, in order to exhibit the mechanism which lies to the rear of said holder. Fig. 3, Sheet 3, is an end elevation of the rear end of the machine, all those 25 portions of the latter which are below the table and also which are at the left of the dotted line y y in Fig. 1 being omitted, the driving-clutch and loose pulley being shown in section. Fig. 4, Sheet 4, is a side elevation of the box for holding the straw or other material with which the collar is to be stuffed 30 and the adjacent mechanism for taking the stuffing material from the box and feeding it into the tube, the latter being shown at its central vertical section and the feed-separator 35 and the side of the box both being partly broken away to show the preferred device for properly pressing the stuffing material down through the box, and the mode in which the feed-separator enters the stuffing material. 40 Fig. 5, Sheet 5, is an end elevation of that side of the collar-holder and clamp which is on the left hand in Fig. 1. Fig. 6, Sheet 5, is an end elevation of the other side of the collar-holder of the clamp fastened thereto, and also showing in section the shell of a collar to be stuffed 45 as held by said clamp. Fig. 7, Sheet 5, represents a cross-section of a portion of the col-

lar-holder, said section being taken at the dotted line z z in Fig. 5, and showing a portion of the end of the collar in position between 55 the opposing lips of said holder. Fig. 8, Sheet 4, represents a top view of the disk or wheel which carries the clamps or clutches by which the collar is held, the clamp-piece E' being omitted and the clamping-screw E' and its 60 nut E^s having been swung around to one side. Fig. 9, Sheet 4, represents a top view, and also a front section, of the feed-separator. Fig. 10, Sheet 3, represents the main lever for operating the feeding-rod, and also showing 65 the slide for guiding the rear end of the said rod and the connection between said slide and the main lever. Fig. 11, Sheet 3, represents a side and also a top view of the stuffing-rod. Fig. 12, Sheet 2, is a side elevation of the front 70 portion of the rod whereby the operator starts or stops the feeding of the stuffing material; and Fig. 13, Sheet 2, represents a view of the same, taken at the rear of the supporting-post, the rod being broken off at the dotted line 2 2 75 of Fig. 12. Fig. 14 represents a side elevation of the rear end of said rod and its rear connections and support. Fig. 15, Sheet 3, shows a top and also a side view of the adjustable block B' , which may be used for supporting 80 the collar during certain of the portions of the process of stuffing the collar. Fig. 16 represents a horse-collar before the ends are sewed or closed together. Fig. 17, Sheet 6, represents a central transverse section of the clamping devices shown in Figs. 4, 5, and 8, the section being taken through a line passing through 85 the center of Fig. 5. Fig. 18, Sheet 6, represents an elevation of that edge of the clamping devices shown in Figs. 4, 5, and 8, and 90 which is on the left hand in Fig. 5. Fig. 19 is a plan showing the relation of the block B' to its support. Fig. 20 is a plan of the front edge of the machine—that is, the end toward the operator—parts of the machine being 95 broken away.

A indicates the frame of the machine, formed in any suitable manner.

B indicates the block which supports the horse-collar, and also the support for the collar-holder C , the latter being secured by bolts or other means to said block. This block B is arranged to slide longitudinally upon the platform A' in any suitable manner, and in the

present instance the edges of the sides of said block rest (see Fig. 2) upon the frame and project under the flanges a' of guides a , secured to said frame.

5 As an additional means of more readily shifting the horse-collar, I preferably provide a block, B' , (shown in Fig. 15,) and pivoted to the block B at the point B' , the pivot B' vertically entering and turning in a suitable opening in the block B . The block B' always rests at its pivoted end or portion upon the block B . The horse-collar to be stuffed is laid upon block B' , and the latter is turned to the right or left and supports the collar when the collar is altogether off from over the block B or is only partially over said block B . This block B' allows the horse-collar while being stuffed to be shifted to a point where, if the block B' were not present, a portion of the 20 collar would be unsupported and would hang over the side of the frame. The advance movement—that is, a movement toward the right in Fig. 1—of the slide-block B is stopped, when desired, by suitable means—as, for instance, by the hand-pawl G , secured to the sliding block B , and the ratchet G' , fixed to the frame, the pawl engaging the ratchet G' except when actually held in disengagement therefrom by the operator.

25 Suitable means are employed to bring the sliding block B (when the pawl G is lifted) toward the feeding-box F to a position which said block will occupy when the operation of stuffing the collar is about to begin. The 30 means here shown consist of a weight, D , whose eye engages hook D' on the pulley D' , in turn supported on the cord D'' , one end of which cord is connected to the frame at D' , and the part of the cord on the front side of 35 the pulley, after passing over the fixed pulley D'' , is connected to the sliding block B at D'' .

The collar to be stuffed is held to the sliding block B and prevented from slipping away from the stuffing-rod as the latter is advanced 40 toward said collar by means of a suitable clamp. In the present instance I employ the collar-holder C , constructed as follows, to engage open ends of the collar:

To a suitable frame, as C' , having opening 45 C' , is connected a lug, C'' , carrying at either end a pivot, C'' , and on the lower pivot is pivoted the swing or clutch-piece C' , and on the upper end is pivoted the swing or clutch-piece C'' . The under edge of the clutch-piece 50 C' is provided with groove C'' , (see Fig. 7,) and the upper edge of the clutch-piece C'' is likewise grooved. There extends from the frame C' at each side of the opening through said frame a flange, C' . Each flange C' carries a vertical lip, C'' . The lip C'' of that flange C' which is located at the upper side of the opening through the frame projects upward, and the lip C'' of that flange C' which is located at the lower side of the said opening 55 through the frame projects downward.

In practice the leather or other flexible material of which the collar is composed is

brought through the opening C' and bent over the flanges C' and the lips C'' , and the lower clutch-piece, C'' , is then brought upon the lower flange C' and the upper clutch-piece C' , brought down against the upper flange, C' , and the two clutch-pieces are then tightly pressed or drawn together by any suitable tightening device, and when so drawn or 70 pressed together the lips C'' will press the material of the collar into their respective grooves, and thus firmly clamp the collar in the holder.

75 A convenient device for tightening or closing the clutches C' and C'' against their respective flange C' and lip C'' , and thereby pinching the leather between the clutch and its said flange and lip, as shown in the drawings, Figs. 5 and 18, is as follows: The forward end of the clutch-piece C' is provided with the vertical extension C'' . To the upper end of this extension C'' is pivoted a rotary thumb-cam, C''' . This cam, when turned, operates on the upper edge of the upper clutch-piece, C' , and moves the latter piece and the lower clutch-piece, C'' , toward each other.

80 The nuts C^{12} and C^{13} operate to hold their respective clutch-pieces C' and C'' to the lug C' and to accommodate the varying thickness of the ends of the material of which the collar-shell is composed. When the collar is to be 85 released from the holder, the cam is turned, the clutch-pieces released and moved around on their respective pivots and away from the flanges C' , when the ends of the collar can 90 be withdrawn from the holder. The position of the clutch-pieces C' and C'' when turned or moved away from the flanges C' also affords a convenient opportunity for introducing through the openings C' the collar to be 95 stuffed and for laying these said ends of the collar upon the flanges C' and the lips C'' thereof. Where the material of which the 100 collar-shell or outside surface is composed has not sufficient strength at the point where it is 105 clamped to the holder by the clutch-pieces C' and C'' to withstand the thrusts of the stuffing-rod while the latter is stuffing the collar, I employ in connection with the aforesaid clamp a supplemental clamp, which I locate at the rear 110 side of the frame C' , and I preferably construct the latter clamp as follows: In the clamp 115 E the clamp-piece E' is pivoted at E'' to the side of the frame C' and has an extension or pivot, E'' , projecting toward and adapted to 120 meet an opposing extension or point, E''' , connected to the frame C' . When the end of the 125 collar is placed through the opening C' and clamped by the clutch-pieces C' and C'' , the clamp-piece E' is moved so that the point E'' enters on one side of the collar between the two enlarged parts E'' E''' of the collar and the other point on the other side of the collar between the two enlarged parts, there being 130 at this narrow part E'' of the collar four laps or layers of material, and the clamp-piece is moved so that the points E'' E''' grasp the narrow part between them and hold at a point where the material of the shell of the collar

is strong, and thus supplement the clamp C and prevent the shell of the collar from being torn at or in the proximity of the clamp C through the thrust of the stuffing-rod.

5 The preferred means for enabling the clamp E' to pinch the collar and retain its hold upon the latter consists of the clamping-screw E', attached to the frame C' and the nut E⁸, screwed onto said screw E', the free end of 10 the lever of clamp E being preferably, as shown, (see Fig. 6,) between the nut E⁸ and the point of the attachment of the screw E' to the frame.

In practice, the collar being clamped by 15 clamp C, the thin part E⁴ of the collar resting on the point E³, the clamp-piece E' is brought down so that its point E² presses the part E⁴ of the collar against said point E³, the screw E' passing up through and beyond the top of 20 clamp-piece E' and the thumb-nut E⁸ being screwed on screw E' and down upon clamp-piece E', thus causing the points E² E' to pinch between them the part E⁴ of the collar.

It is very desirable that during the operation 25 of stuffing the collar the latter should be turned, so as to enable the operator to ascertain how each portion of the collar is being stuffed and to facilitate the placing of the wad of stuffing material introduced into the collar 30 by the stuffing-rod at the desired place within the collar. To enable the collar to be thus turned, I construct the frame C' so that it can be turned. The preferred mode of construction consists in providing said frame with an 35 annular border, C¹⁴, having a peripheral groove, C¹⁵, and this annular border rests upon and turns within a concave frame, C¹⁶, whose inner edge is provided with tongues C¹⁷, which fit within the groove C¹⁵. This tongue and 40 groove and the action of the frame C¹⁶ combine to prevent vertical displacement of the frame C', and at the same time allows the frame to be turned in the direction of the length of its periphery.

45 The feed-box F is suitably upheld, as by supports F', attached to the platform A. The lower portion of the box is narrowed, as shown, the two pieces F² forming the sides being inclined toward each other as they descend and 50 leaving between them an opening, F⁸, in length a little greater than the desired length of the straws, grasses, or other fibers to be used in stuffing the collar. The length of the opening F⁸ is preferably, as shown, at right angles 55 to the length of the machine.

In order to evenly feed the straw ordinarily used in stuffing collars down through the feed-box, a feeding device is required, and a preferred construction of such device is shown in 60 Figs. 1 and 4, where the reciprocating vertical piece F⁴, located at or near the center of the feed-box, is provided with one or more pairs of fingers, F³, pivoted at F¹ and pointing outwardly and downwardly in opposite directions and prevented from turning back too far by means of a shoulder, F⁵, formed upon each and impinging against the stop F⁶, fixed to

the said reciprocating piece F⁴. These fingers F³ operate to close toward each other as piece F⁴ rises, and thus allow the straw to slip by them, and then operate to open as the piece F⁴ descends and force the straw before them down toward and through the opening F⁸.

The straw is prevented from falling through the opening F⁸ by means of gages F⁹, extended 75 across the lower opening, F⁸, of the feed-box in a direction transverse to the length of the straw, one gage near each end and extending across the open bottom of the feed-box. These gages consist, preferably, of two beams or 80 bands, and are adjustable in such a manner that the amount of straw to be fed to the stuffing-rod can be regulated at pleasure.

The preferred construction for rendering these gages adjustable is as follows: The gages 85 are pivoted at one end to the box at F¹⁰, and their free ends are pivoted at F¹¹ to the sliding gage-rod F¹², which has a slot, F¹³, (see Fig. 2,) through which passes a thumb-screw, F¹⁴, engaging a female screw, F¹⁵, in the side 90 of the box F. By loosening and tightening this thumb-screw F¹⁴ the sliding gage-rod F¹² can be elevated or depressed, and thus the gages F⁹ be likewise elevated or depressed at one end, while turning on their pivots at the other. 95

The forward end of the box F is preferably provided with the guides F¹⁶, which latter operate to guide the straw which has been just caught by the stuffing-rod, and also to bend it (this straw) back, so as to throw it into a compact position along the stuffing-rod in proper condition to be carried into the tube R by the said stuffing-rod.

The device for positively separating the amount of straw which it is desired that the 105 stuffing-rod shall take at each stroke and shall carry into the collar consists, primarily, of the feed-separator H. (See Figs. 1 and 4.) This separator H has a back, H', and from the edges of this back the flanges H² project down, these 110 flanges being placed sufficiently far apart to allow the head of the stuffing-rod to pass (as it does) between them.

The separator consists of a rocker-shaped piece, H', suspended from the bars H⁴ by braces 115 H³, which are bolted or screwed to downwardly-projecting flanges H² from the sides of the rocker H'. The curve of the upper surface of H' is such that the swinging of the bars H⁴ on their pivots will carry the rocker 120 closely under the lower edges of the sides F² of the hopper. The lower edge of the flanges H² is curved on a shorter radius. The separator is thus in effect a curved shuttle, which is swung under the hopper, its forward end 125 entering the straw and separating all that is below the curve of the upper surface of the part H'. The space between the flanges H² permits the passage of the stuffing-rod K.

The separator is suitably supported and is 130 preferably upheld, as shown, by the braces H³, which extend laterally one from one side and the other from the other side of the separator beyond the sides of the box F, and are then

connected to the swinging rods H^4 , which latter are pivoted at H^5 to said box (see Figs. 1 and 2) and are each provided at its upper extremity with an arm, H^6 , to whose free end is attached a spring, H^7 , strained between said end and a point, as H^8 , of the box, at which point H^8 the lower end of the spring is attached. This spring is the preferred form of mechanism for retracting the separator H after it has been forced into the straw. The forward movement of the separator, whereby it is caused to enter the straw, is effected through any desirable agency. A preferred means is the rod I , forked at I' , one branch of which fork is connected to that swinging rod H^4 which is on one side of the feed-box and the other branch is connected to that swinging rod H^4 which is on the other side of the feed-box. When the separator is moved forward, it enters the straw, and by reason of its wedge shape it forces down all that portion of the straw which comes below its point. Obviously this amount of straw will be much or little, according as the gages F^9 are lowered or elevated.

The stuffing-rod K consists of a rod, K^2 , and a head, K' . (See Figs. 4 and 11.) This head is laterally flattened, as shown in Fig. 11, and is concave at the forward end to enable the straw to be more securely retained by said end while the latter is carrying the straw into the collar.

The stuffing-rod is suitably supported and preferred means for supporting it are—

First. The bearing L , by which the forward portion of the rod is supported and through which the rod slides.

Second. The slide-rods M M' . (See Figs. 1 and 3.) These slide-rods M support the slide K^3 , fixed by set screw K^4 to the rear portion of the stuffing-rod K , the rods M passing through the slide K^3 and the latter sliding on said slide-rods. The rods are supported, preferably, by standards L' and M' .

Below the feed-box F and under the stuffing-rod K when the latter is moved forward to stuff the collar is the table or platform P , which helps to prevent the straw from crowding downward and away from the stuffing-rod as the head of the latter is taking straw from the feed-box, and also catches any loose straws falling from the head of the stuffing-rod and from the bottom of the feed-box and holds them up, so that the head of the stuffing-rod at its next forward movement can take them up and carry them into the collar.

The tube R is located at the forward portion of the machine and is supported at its rear end only by the standard R' . (See Figs. 1 and 4.) The rear end of this tube is preferably provided with a flared extremity, R^2 , the better to admit the head of the stuffing-rod and its accompanying charge of straw to the tube, and while thus compressing this straw around the rod does not break the same, as would be the case were the rear entrance of the tube angular instead of flared. The functions of this tube R will be apparent hereinafter when the

mode in which the stuffing-rod and its accessories operate is described.

A desirable means for imparting motion to the slide K^3 , and hence to the stuffing rod, consists (see Figs. 1 and 10) of the lever S , whose upper end is swung on a pivot, S' , supported by the upright A^2 of the frame A , and whose free end is bifurcated, and each branch of said fork is respectively connected to its respective side of the slide K^3 by a connecting-rod, S^2 , these connecting-rods S^2 being fastened to the slide and lever S by pivoted connections.

A connecting-rod, S^3 , is at one end pivoted to the lever S and at its other end is pivoted to the gear-wheel S^4 at or near the perimeter of the latter. This wheel S^4 is fixed on a shaft, S^5 , (see Figs. 1 and 3,) journaled on the upright A^2 , and its teeth engage a pinion, S^6 , fixed on a shaft, S^7 , which latter also carries the gear S^8 , the pinions S^6 and gear S^8 being preferably made of one and the same piece of metal.

A preferable means of imparting motion to the rod I , which moves forward the swinging rods H^4 and the feed-separator, is as follows:

The rod I is provided with a triangular driving lug, T , which preferably slides upon the rod and is capable of being fixed to the latter at any desired point thereon by means of the set-screw T' .

A pin, T^2 , is fixed in the lever S , (see Figs. 1 and 10,) and as this lever moves backward it passes under and raises said driving-lug T , and thus gets to the rear of the latter. As the lever S moves forward, the pin T^2 impinges against the rear end of the driving-lug T and moves the latter and rod I and the feed-separator H forward.

In order to regulate the length and position of the throw imparted to the feed-separator, I employ two devices, as follows: To attain a desired point in the arc described by the pin T^2 where the latter in its forward movement shall first impinge against the back edge of the driving-lug T , I move the latter along the rod I and set it by means of the set-screw T' . To attain a desired point in the arc described by the pin T^2 where the latter in its forward movement shall stop pressing the lug T forward and leave the same, I employ a device, as standard T^3 , provided with a slot, T^4 , and adjustable slide T^5 . (See Figs. 1 and 3.) The end of rod I passes through this slot T^4 and rests upon the adjustable slide T^5 .

When it is desired that the pin T^2 shall leave the driving-lug T quite quickly—that is, at the lower portion of the arc described by said pin—the adjustable slide T^5 , which supports the rod at or near its rear end, (see Figs. 1 and 3,) is set high, and the rod I and driving-lug T are thus elevated, and when a contrary effect is desired the rod I and driving-lug T are set low by setting the slide T^5 low on its standard T^3 . Thus the length of the stroke of the driving-lug T for the rear half of the arc described by pin T^2 is regulated by the adjustment of the lug T upon the rod I , and the

length of the stroke of the lug T for the forward half of the arc described by the pin T² is regulated by the adjustment of the slide T⁵. Thus the length of the stroke of the feed-separator H and the position of its stroke in relation to the feed-opening F⁸ is easily and perfectly adjusted and regulated.

The object in regulating the position of the stroke or movement of the feed-separator is to regulate the time when in relation to the stroke of the stuffing-rod the feed-separator shall begin its work of separating the straw and feeding the latter to the said stuffing-rod. This capacity for regulating the position and 15 length of the stroke enables the operator to improve the feeding action of the machine and adapt such action to the size of the charge of the feeding material required, and also to the kind of feeding material used. The rod 20 I is so bent at T⁷ as to allow the pin T² to pass above and below the rod I.

A preferred form of device for stopping or starting the action of the feed-separator consists (see Figs. 1 and 3) of the rod U, whose 25 rear end is pivoted to and supported by a right-angled lever consisting of the arm U², pivoted to the standard U³, and the arm U⁴, extending under the rod I and at right angles to the latter. The forward free end of this rod 30 U is supported by and slides in the slotted support U⁵, attached to the upright F¹. (See Figs. 1 and 12.) This rod has at its forward end a notch, U⁶, and a pin, U⁷. To stop the action 35 of the feed-separator, the rod U is pushed back until the notch U⁶ engages the bottom of the slotted support U⁵, when the arm U⁴ of the right-angled lever will lift the rod I so high that the pin T² can no longer engage the driving-lug T.

40 To start the action of the feed-separator, the rod U is lifted out of the notch U⁶ and disengaged from the slotted support U⁵, and then the weight of the rod U will cause the right-angled lever to descend and allow the rod I to 45 drop into position, where the driving-lug T will engage with the pin T², the rod U being at the same time forced forward until the pin U⁷ strikes the slotted support U⁵, when the rod U will be brought to rest.

50 A preferred form of mechanism for imparting a reciprocating motion to the piece F⁴ of the feed-box F consists (see Figs. 1 and 2) of rod V, pivoted at V¹ to lever S, and sliding in the slot V² of the lever V³, fixed to shaft V⁴, which 55 latter is rigidly connected to the levers V⁵. One of the levers V⁵ is at one side of the feed-box and the other lever V⁵ is at the other side of the feed-box. Connected to the upper or 60 free ends of the levers V⁵ and extending between them is the rod V⁶, which latter is pivoted to piece F⁴ at V⁷. The lever V⁵ is provided at its lower end with the lug V⁸, which latter, as the rod V is moved from the rear toward the front of the machine, engages a stop-pin, V⁹, and thus prevents the piece F⁴ from 65 being raised too high.

Between a nut, V¹⁰, on the front end, V¹⁰, of

the rod V and a sliding thimble, V¹¹, sliding on said rod, is a spiral spring, V¹², on the rod V.

A stud, V¹³, on the top of the rod prevents 70 the thimble V¹¹ from sliding too far rearward. By screwing the nut V¹⁴ forward or backward the spring can be more or less compressed, as desired.

In operation as the lever S moves rearward 75 the thimble V¹¹ impinges against the lever V³, and, drawing it rearward, depresses the free ends of levers V⁵, thereby depressing the piece F⁴, and, forcing down the fingers F³, feeds down the stuffing material. As the fingers continue 80 to descend, the resistance of this material finally stops the descent of the fingers and the forward movement of the lever V³, when, as the rod V continues to move rearward, the spring V¹² will yield and the thimble V¹¹ and nut V¹⁴ 85 be brought toward each other, the spring being compressed between them.

One great advantage of the spring V¹² is as follows: When the feed-separator has been adjusted to feed but a little of the stuffing material at each stroke, the fingers will often feed the stuffing material down faster than the feed-separator takes it away, and in such event the fingers in their downward stroke will at each successive stroke be stopped at a higher point 95 above the bottom. The spring allows the lever V³ to give way at any point as soon as the fingers have firmly pressed down the stuffing material, and thus prevents the latter from being too much compressed, and also prevents 100 any part from being broken. The pressure of the fingers upon the stuffing material can also be increased or diminished by screwing the nut V¹⁴ forward or backward.

In order to render the operation of the piece 105 F⁴ and its accompanying parts more easy and regular, it becomes desirable to counterbalance the weight of the piece F⁴, fingers F³, and lever V⁵.

Any suitable device which will cause the levers V³V⁵ in their movement toward the front 110 of the machine to rise may be employed. A preferred form of device consists of the weight V¹⁵, suspended from arm V¹⁶, keyed or otherwise fixed to the shaft.

The gear S⁸ is turned by any suitable mechanism. In the present instance the gear S⁸ (see Figs. 1 and 3) engages the pinion W, fixed to one end of the shaft W¹, which latter is journaled on the upright A², and at its other end supports the friction-clutch W², arranged 120 to slide upon the shaft and connected thereto by a feather, so that the rotation of the clutch will rotate the shaft. The driving-pulley W⁴ rotates loosely upon the shaft W¹, and when the friction-clutch is pressed against said pulley the latter causes the clutch to rotate, and thereby communicates motion to the machine. When the clutch is no longer pressed against the pulley by the spring W⁵, the spring compressed between the clutch and the pulley 125 throws the clutch away from the pulley and the latter ceases to drive the machinery. The rod X (see Fig. 1) is a mere brace connecting the upright A² and the lower portion of the

frame and stiffening the same. The clutch W^2 is moved against the pulley W^4 by any desired mechanism.

- A preferred form of device for this purpose 5 consists as follows, viz: The bent lever Y (see Fig. 3) is pivoted at Y' to the arm Y^2 of the upright A^2 . The free end of the upper arm of said lever Y is bifurcated at Y^3 , and the forks enter, respectively, the slots Y^4 in the collar 10 Y^5 , fixed loosely on the shaft W' , behind the clutch. A rear elevation of this collar detached is shown in Fig. 3. The free end of the lower arm of the lever Y is connected to the upper end of a rod, Y^6 , (see Figs. 3 and 1,) 15 whose lower end is connected to the free end of a lever, Y^7 . The other end of this lever is fixed to the shaft Y^8 , and this shaft carries a lever, Y^9 , from whose free end hangs the weight Y^{10} , and also carries the lever Y^{11} , to whose 20 free end is connected one end of the rod Y^{12} , the other end of said last named rod being connected to the free end of lever Y^{13} , the other end of the latter being fixed to shaft Y^{14} . (See Figs. 1 and 2.) This shaft Y^{14} carries lever 25 Y^{15} , to whose free end is connected the upper end of the treadle-rod Y^{16} , the lower end of this treadle-rod being connected to the treadle Y^{18} , the latter at its rear end being pivoted to the hangers Y^{19} .
- 30 The platform Y^{20} supports the operator while stuffing the collar, and the end Y^{21} of the treadle is so raised that when at rest this end Y^{21} shall be somewhat higher than is the upper surface of the platform Y^{20} .
- 35 In practice the operator stands with his right foot at Y^{22} , his left foot being at Y^{23} , and his heel resting on the end Y^{21} of the treadle. To depress the treadle, the operator bears down 40 on his left heel, his left foot being at the same time supported by the platform. Thus, while operating the treadle, his equilibrium is in no wise disturbed, as would be the case were his whole foot to rest upon and descend with the treadle. The depression of the treadle operates through the system of levers and rods described to draw down the free end of the lower arm of the lever Y (see Fig. 3,) and cause the free end of the upper arm of said lever to press the clutch W^2 against the pulley 45 W^4 , and thus start the machine into action. When the operator releases his pressure on the treadle, the spring W^5 throws the clutch W^2 away from the pulley W^4 and stops the machine, and at the same time the weight Y^{10} 50 operates to retract the rod Y^{12} and raise the end of the treadle again above the surface of the platform.
- The individual operation of the several portions of my machine has been already described in connection with descriptions of the construction of said portions.
- 55 The operation of the machine is as follows: The feed-box is filled with stuffing material. Suppose the rim E^6 (see Fig. 6) of the collar is first to be stuffed. The end of the collar is properly fastened in the clamps or clutches and the block B is moved forward, and the

end of the tube enters the open end of the collar. The operator now starts the machine in action by depressing the treadle Y^{18} . The 70 main part of the collar is upheld by the operator. The feed-separator H draws down the straw, and the head of the stuffing-rod K takes the straw drawn down by the feed-separator and carries it through and beyond the tube, 75 and deposits it within the collar at or near the center of the rim. The succeeding strokes of the stuffing-rod K gradually fill the collar. As the collar is gradually filled with straw, the head of the stuffing-rod will pack the straw 80 within the collar, exerting a force in packing equivalent to the resistance offered by the weight D , and when the straw in the collar has become packed sufficiently to make a resistance to the head of the stuffing-rod equal 85 to the resistance offered by the weight the stuffing-rod will move the collar and block B away from the feed-box. This operation of stuffing and packing is continued until the rim is filled to the end, at which time one-half 90 of the rim has been stuffed. For some time before the said one-half of the rim has been stuffed the clamped end of the collar has left the free end of the tube and there is quite a space between said ends. The tube still remains useful, as the straw around the head of the stuffing-rod would fall off before the said head reached the collar were it not for the tube. The clamped end of the collar is then 95 released from the clamp and the other end of the rim is clamped and stuffed in the same manner as the first half of the rim was clamped and stuffed. The bulges E^6 (see Fig. 6) of the collar are next to be filled. Before being placed on the machine they are preferably 100 loosely filled with cut or fine straw. Then the free end of one of the bulges is clamped to the clamp C . The block B is then moved toward the feed-box, the tube entering the bulge and passing through the loose fine straw to or near 105 that end of this bulge which is at the center of the collar.

The operation of stuffing the bulge is similar to the aforescribed operation of stuffing the rim. During the process of stuffing the 110 bulge when it is found necessary to the collar, either for the purpose of symmetrically shaping it or for any other reason, the block B' is placed on block B and under the collar, the pivot B^3 of the block B being inserted at B^3 in 115 block B and the collar allowed to rest thereon. The other bulge of the collar is stuffed in a manner similar to that in which the first-named bulge was stuffed. When it is desired to pack the incoming charge of straw with 120 more force than the resistance of the weight will impart, the operator presses the collar toward the stuffing-rod as the latter advances, and when he desires the stuffing-rod to pack with less force than the resistance of the weight 125 D imparts he pulls on the collar in a direction which is away from the stuffing-rod.

During the operation of stuffing the collar it is sometimes found necessary after several

wads or charges of straw have been placed in the collar to pack these charges more closely before feeding any more stuffing material into the collar. To accomplish this result, the operator shifts the rod U toward the rear end of the machine until the notch U⁶ engages with the bottom of the slotted support U⁵, when, as aforescribed, straw will no longer be fed to the stuffing-rod and the latter will enter the collar without any charge of straw, and will, as aforesaid, pack more closely the straw already within the collar.

In stuffing it is very desirable to turn the collar while clamped so as to bring uppermost these parts of the collar which are underneath, in order to enable the operator to more clearly see how perfectly all parts of the collar are being stuffed, and to better enable him to place the charges of straw where necessary and to pack or pound the collar at the point where such packing or pounding is necessary.

The formation of the circular clamp-frame and bed enables the collar to be turned at will with facility.

Another advantage of the tube is that in stuffing the bulge it (the tube) passes through the loose fine straw which has been previously inserted into the collar by hand, and the free end of said tube is near that end of the bulge which is at the center of the collar, the loose straw being on all sides of said tubes. As the operation of stuffing goes on, the loose straw is everywhere mixed with the straw introduced by the rod.

If the tube were not present, the incoming stuffing-rod would crowd all the loose straw into one end of the bulge, leaving the other end to be filled with the long straw alone.

One or more of the various features of my invention may be used together or in connection with devices for stuffing other than those shown herein. All such applications and uses will fall within the scope of my invention.

What I claim as new, and desire to secure by Letters Patent, is—

1. In a collar-stuffing machine, the sliding block B, the collar-holding clamp adapted to rotate thereon, pawl G and ratchet G', and means, substantially as described, for drawing the block B toward the feed-box and resisting the advance of the stuffing-rod, substantially as and for the purposes specified.

2. In a collar-stuffing machine, the sliding block B, pawl G and ratchet G', and weight D, pulleys D² D⁵, and cord D³, in combination with the reciprocating stuffing-rod, substantially as and for the purposes specified.

3. In a collar-stuffing machine, a rotating frame mounted on the platform of the machine internally provided with a suitable clamp or clamps, substantially as and for the purposes specified.

4. In a collar-stuffing machine, the concave frame C¹⁶ and the circular frame C¹⁴, adapted to rotate thereon and provided with a suitable clamp or clamps, substantially as and for the purposes specified.

5. In a collar-stuffing machine, the concave frame C¹⁶ and circular frame C¹⁴, adapted to rotate thereon and provided with the tongue 7⁷ and groove for retaining the circular frame on the concave frame, all in combination with a clamp or clamps for clamping the end of the collar, substantially as and for the purposes specified. 75

6. The clamp E, consisting of the flanges C⁷ and the arms C⁴ and C⁵, secured to a support by pivots, (an orifice being present between said flanges,) and suitable means for causing the free ends of the clamps to pinch between 80 them the end of the collar, substantially as and for the purposes specified.

7. The clamp C, consisting of the flanges C⁷, each provided with a lip, C⁸, and separated by the orifice C⁹, and the arms C⁴ C⁵, secured to a 85 support by pivots, and the thumb-cam C¹¹, substantially as and for the purposes specified.

8. The clamp E, consisting of the movable arm E', provided with jaw E² and opposing stationary jaw E³, the latter being located at 90 or near the middle of orifice C⁹, and means for causing the jaws to pinch that part of the collar which is between the rim E² and the bulge, substantially as and for the purposes specified. 95

9. The clamp E, consisting of the movable arm E', pivoted at E⁹ and provided with jaw E² and opposing stationary jaw E³, located at or near the middle of the orifice C⁹, and the screw E⁷ and thumb-nut E⁸, substantially as 100 and for the purposes specified.

10. In a collar stuffing machine, a feed-box provided with a feed-opening, F⁸, in combination with the adjustable gages F⁹, extending across said opening, substantially as and for 105 the purposes specified.

11. In a collar-stuffing machine, the combination of a feed-box provided with feed-opening F⁸ and the gages F⁹, pivoted at F¹⁰ and crossing said opening, and arranged to allow 110 the feed-separator and stuffing-rod to pass between them, and the sliding gage-rod F¹² and nut F¹⁴, substantially as and for the purposes specified.

12. In a collar-stuffing machine, the combination of a feed-box and the reciprocating piece F⁴, and the fingers F⁵, so adapted that their free ends shall approach each other as the piece F⁴ rises and separate as the said piece F⁴ descends through the straw, substantially as 115 and for the purposes specified. 120

13. In a collar-stuffing machine, the combination of the feed-box F and reciprocating piece F⁴, and the fingers F⁵, pivoted at F⁶ and provided with shoulders F⁷, and the stop F⁸ on 125 piece F⁴, substantially as and for the purposes specified.

14. In a collar-stuffing machine, the combination of reciprocating piece F⁴ and the reciprocating rod V, and the lever V³ and levers V⁵, rigidly fixed to shaft V⁴, spring V¹², nipple V¹¹, stud V¹³, and nut V¹⁴, and means for elevating the piece F⁴ when depressed, substantially as 130 and for the purposes specified.

15. In a collar-stuffing machine, the combination of reciprocating piece F¹ and the reciprocating rod V, and the lever V² and levers V³, rigidly fixed to shaft V⁴, spring V¹², nipple V¹¹, 5 stud V¹³, and nut V¹⁴, lever V¹⁵, rigidly attached to shaft V⁴, and weight V¹⁶, substantially as and for the purposes specified. 45
16. In a collar-stuffing machine, the combination of the reciprocating stuffing-rod and the reciprocating feed-separator, substantially as and for the purposes specified. 50
17. In a collar-stuffing machine, the combination of the reciprocating stuffing-rod and the feed separator, consisting of the pendent levers and the supported piece H and side pieces, H², and adapted to allow the stuffing-rod to reciprocate between said side pieces, substantially as and for the purposes specified. 55
18. In a collar-stuffing machine, the feed separator consisting of the curved back or main piece, H¹, and pointed side pieces, H², curved on their lower edges, said piece hung on pendent levers attached to the hopper, substantially as and for the purposes specified. 60
19. In combination with the feed-separator H, the arms H⁴, pivoted to the hopper at or near their upper ends, and means, substantially as described, for imparting a reciprocating motion to the same, substantially as and for the purposes specified. 65
20. The combination of the feed-separator H, the swinging arms H⁴, lever H⁶, respectively fixed to said arms, spring H⁷, and rod I, substantially as and for the purposes specified. 70
21. The combination of the feed separator H, the swinging arms H⁴, levers H⁶, respectively fixed to said arms, spring H⁷, and rod I, connected, substantially as described, to said levers H⁴ and provided with driving-lug T on said rod, and the reciprocating pin T², adjustable substantially as and for the purposes specified. 75
22. In a collar-stuffing machine, the combination of the reciprocating feed separator and rod I, provided with driving-lug T, pin T², and rod U, having at one end a notch, U⁶, and pin U⁷, with the slotted support U⁵ and the right-angled lever U', substantially as and for the purposes specified. 80
23. In a collar-stuffing machine, the combination of the reciprocating feed-separator and rod I, provided with driving-lug T, pin T², and rod U, having at one end a notch, U⁶, and pin U⁷, slotted support U⁵, and the right-angled lever U', and adjustable support T³, substantially as and for the purposes specified. 85
24. In a collar-stuffing machine, the combination of the stuffing-rod, slide K¹, slide-rods M, connecting-rod S², and lever S, substantially as and for the purposes specified. 90
25. In a collar-stuffing machine, the combination of the stuffing-rod K and lever S, and connecting mechanism for enabling said lever to operate said rod, and feed-separator H, and rod I, and driving-lug T, and pin T², located on said lever S, substantially as and for the purposes specified. 95
26. In a collar-stuffing machine, the combination of the collar-supporting mechanism, lever S, rod V, pitman S², and mechanism for imparting a reciprocating movement to the latter, substantially as and for the purposes specified. 100
27. In a collar-stuffing machine, the combination of the collar-supporting mechanism, the swinging lever S, rod V, and stuffing-rod K, and connecting mechanism for enabling the lever S to operate the stuffing-rod, and rod I, and mechanism for enabling the lever S to operate said rod I, substantially as and for the purposes specified. 105
